UNITED STATES PATENT OFFICE

FRANKLIN H. MACKENZIE, OF BYWOOD, PENNSYLVANIA

RADIOFREQUENCY AMPLIFYING SYSTEM

Application filed August 1, 1925, Serial No. 47,516. Renewed January 6, 1930.

My invention relates to radio receiving apparatus.

The object of the invention is to provide a receiving circuit having a number of stages of radio frequency amplification wherein certain elements of the tuning devices may be caused to produce a regenerative or feed-back effect, from stage to stage; that is, the feed-back takes place not between the elements of a single audion, but between coils in the circuits of the several tubes. This is accomplished, say in a two-tube receiving set, by rotating the coil or coils of the central tuned circuit until the maximum permissible feed-back occurs between it and the two outer coils.

This circuit is characterized by a peculiar roaring sound, on both sides of which a position of clear reception is located, instead of having a zone of clear reception between two zones of roaring (or whistling) as in the ordinary regenerative circuit. I believe this roar in my set is due to the successive beat notes of the two tubes, not the self oscillation of a single tube.

Broadly stated the invention comprises a method of operating a radio frequency amplifying system, which system comprises at least three tuned radio frequency transformers interconnecting thermionic devices, one of said transformers being adjustable with reference to the other two, and the improvement in the method comprising adjusting the one transformer with reference to the other two so that the maximum useful feed back of energy occurs between the adjustable transformer and the other two, and regulating the system in such a manner that substantially no self-oscillation occurs in the thermionic devices.

A clearer understanding of the invention will be obtained from the following specification and the drawing accompanying the same.

In said drawing:

The figure represents a reflex circuit of otherwise well known type, but modified to embody my invention.

While it is, of course, obvious that my invention may be applied to any circuit employing several stages of radio frequency amplification, it is unnecessary to illustrate said

multiplicity of circuits, and a single circuit is, therefore, described in detail. The figure shows a reflex circuit comprising an antenna 1 connected to the ground at 26 through inductance 2. In inductive relation to coil 2 is another inductance 3 connected in parallel with variable condenser 4, elements 3 and 4 jointly constituting a tuned circuit connected to the grid 21 of audion 5 and grounded through the secondary winding of transformer 7 to ground 26. The filament 20 of this audion is energized by the usual battery A, a rheostat 9 being interposed in the negative lead, as shown.

The positive terminal of the high-voltage battery B is connected to the plate 22 of this audion through coil 12 and the primary of transformer 8. A protective resistance 10 is connected between the positive terminal of the A-battery and the negative terminal of the B-battery, as shown. This may be of the character disclosed and claimed in the co-pending application, Serial No. 690,169, filed February 2, 1924.

Coil 13 is placed in inductive relation to coil 12, and is connected in parallel with the variable condenser 14, as shown. This combination constitutes a tuned circuit which is connected to the negative terminal of the battery A through the secondary winding of transformer 8, and to the grid 24 of audion 6. The filament 23 of said audion is energized by battery A, as shown, a rheostat 11 being interposed in the negative side of the circuit. The positive terminal of battery B is connected to the plate 25 of the audion by a circuit including the telephone receivers 18 and inductance 15 in series.

Coil 16 is inductively related to coil 15, which, in parallel with variable condenser 17, constitutes a tuned circuit. This circuit is connected to the primary winding of transformer 7, a crystal detector or other rectifying means 19 being interposed in series in said connections.

In operation, the incoming radio frequency currents are passed from the antenna coil 2 to grid 21 by means of the tuned radio frequency circuit 3, 4; are amplified by audion 5 and passed on to audion 6 by coil 12 and

tuned radio frequency circuit 13, 14 to the grid 24. The audion 6 feeds the further amplified currents from coil 15 to the tuned radio frequency circuit 16, 17, whence they pass through rectifier 19 into the primary of transformer 7, as shown. Because of the action of rectifier 19, however, the impulses have now become unidirectional impulses of audio frequency which produce audio frequency alternating circuits in the secondary of transformer 7. These audio frequency circuits are passed to grid 21, and amplified currents of similar nature are produced in the output circuit which pass into the transformer 8 and thence to grid 24. After further amplification by audion 6, the currents produce corresponding sounds in the telephone 18.

The desired maximum useful feed back action may be obtained by turning the center coil 12 or coils 12, 13, so that its turns are at or nearly at right angles to the end coils. The outer or end coils are then turned to resonance, and a roar is produced, leaving the center coil at or nearly at the right angle position, and turning the end coils slightly out of resonance. This results in bringing in the signals with decidedly better amplification than other radio frequency circuits. It is found that by operating in this manner, a point may be reached where self-oscillation of the tubes or thermionic devices is substantially eliminated.

Having thus described my invention, what I claim as new and desire to secure by Letters Patent is:

The method of operating a radio frequency amplifying system, which system comprises at least three tuned radio frequency transformers interconnecting thermionic devices, one of said transformers being adjustable with reference to the other two, the improved method comprising adjusting the one transformer with reference to the other two so that maximum useful feed back of energy occurs between the said adjustable transformers and the other two and regulating the system in such a manner that substantially no self-oscillation occurs in the thermionic devices.

In testimony whereof I affix my signature.

FRANKLIN H. MACKENZIE.
